METHOD AND MEANS FOR REPRESSING BRICKS.

Application filed July 14, 1926. Serial No. 122,402.

My invention relates to brick repressing. The object is to provide improved method and means for securing repressed bricks of uniform dimension. The invention includes 5 method and means for pressing the clot by uniformly moving elements to secure all the margins of constant uniform dimension. This result is secured by providing means for permitting a panel to be formed on one 10 face of the brick during the pressing operation to take care of the surplus clay in the clot, and then removing the panel from said face. This panel may be removed in such way as to leave a slight depression 15 within the surrounding margins of said face to facilitate stacking and laying. The invention also comprises method and means for pressing two or more clots simultaneously, so as to secure uniform dimension of each brick notwithstanding the fact that the different clots contain different quantities of material.

The invention also comprises improvements in details of construction.

Referring to the drawings, which illustrate merely by way of example suitable means for effecting the invention:—

Fig. 1 is a front elevation.

Fig. 2 is a section on line 2, 2 of Fig. 1.

Fig. 3 is a section on line 3, 3 of Fig. 1.

Fig. 4 is a section on line 4, 4 of Fig. 2.

Fig. 5 is a section on line 5, 5 of Fig. 1.

Fig. 6 is a section on line 6, 6 of Fig. 3, the parts being in different positions.

Figs. 7, 8 and 9 are sections similar to that shown in Fig. 6, with the parts in still different positions.

Fig. 10 is a section on line 10, 10 of Fig. 1.

Fig. 11 is a fragmentary elevation of the valve actuating mechanism.

Fig. 12 is a similar view with parts in different positions.

Fig. 13 is a section on line 13, 13 of Fig. 2, on an enlarged scale.

Fig. 14 is a fragmentary elevation showing the cutting blade and associated mechanism on an enlarged scale.

Fig. 15 is a fragmentary elevation showing the cutting blade in different position.

Fig. 16 is a front elevation of same.

Fig. 17 is a section on line 17, 17 of Fig. 16.

Fig. 18 is a section on line 18, 18 of Fig. 17.

Fig. 19 is a section on line 19, 19 of Fig. 17.

Fig. 20 is a fragmentary section of the cutting blade on an enlarged scale.

Fig. 21 is a view similar to Fig. 14, except that cutting wires are shown in place of the cutting blades.

Fig. 22 is a view similar to Fig. 16 with cutting wires substituted for a cutting blade.

Fig. 23 is a view similar to Fig. 15, with a cutting wire substituted for the cutting blade.

Fig. 24 is a section on line 24, 24 of Fig. 22.

Fig. 25 is an elevation showing the wire tensioning device shown in Fig. 22, on an enlarged scale.

Fig. 26 is an enlarged section of the cutting wire and slicker blade.

Similar numerals refer to similar parts throughout the several views.

As is well known in the art, it is not possible to make brick for repressing either by the soft mud or by the stiff mud process, that all have the same amount of material in them. There is always more or less variation, which, in the usual method of repressing, makes a variation in the thickness of the finished brick.

In the manufacture of fire brick it is especially desirable that the bricks are uniform in thickness as well as uniform in other dimensions. Usually represses are provided with relief springs to take care of surplus material in the brick, thus giving practically a uniform pressure to all the bricks, although there is a variation in thickness to a greater or less degree, depending on the accuracy and temper of the bricks as made before repressing.

In accordance with the present invention, a projecting panel is formed on the upper flat face of the brick. This panel represents the surplus material in the clot from which the brick is pressed. This panel is then shaved off, leaving the brick true to dimension.

Brick represses now in common use comprise a mold box and upper and lower

plungers operating upon the clot within the mold block, and these common features need not be described specifically.

In accordance with the present invention 5 the upper plunger comprises two parts; the panel element and the frame element surrounding it. The panel represents from forty to fifty per cent of the surface or face of a brick of standard size.

10 The machine is usually built to repress two bricks at a time, so that the upper and lower plungers and the mold boxes are shown in duplicate.

15 The upper plungers are mounted on the cross-head 30 which slides up and down between suitable guides. At each end of the cross head is journalled, as at 31, the upper ends of two connecting rods 32. The lower ends of these connecting rods are journalled 20 to cranks 33, both cranks being on the same shaft 34, see Fig. 5.

25 The lower plungers 35 are mounted on the cross head 36. The movement of this cross head is controlled by the large cam 37 mounted on the crank shaft 34 and directly under the lower plunger 35, movement being communicated from the cam 37 to cross head 36 through the antifriction roller 38. The crank shaft 34 is provided with the gear wheels 39 driven by the pinions 40 on 30 shaft 41 driven by pulley 42.

35 The charging device comprises the frame 43 having the tandem charging elements 44 and 45. This frame is operated through connecting rods 43' by arms 46 mounted on the shaft 47. On shaft 47 is also mounted the arm 46' provided with the roller 48, operating in the channel 49 of cam wheel 50, which is mounted on the crank shaft 34.

40 The tie frame 51 at the top of the press is made hollow, forming a tank which is filled with suitable oil for oiling the surfaces of the brick and the table on which it slides. Pipes 52 from this tank are arranged to drip oil on the roller 53 to oil the top surface of the brick as it is fed by the charger, other pipes 54 are arranged to drop a small amount of oil on the part of the feed table 55 over which the bricks slide. All of these 50 pipes are controlled by suitable valves as shown. This oiling system is in accordance with the usual practice.

45 As above stated the upper plungers are composite, comprising the panel elements 56 and the surrounding frame elements 57. The frame elements or portions 57 are connected directly to the cross head and are given positive movement without any relief springs, thus making the brick to thickness, 60 except as to the panel. The panel elements 56 are mounted on the piston rods 58, connected to pistons 59 operating in cylinders 60. The compression springs 61 engaging the underside of pistons 59 tend to maintain 65 the panel elements elevated against the pres-

sure in cylinders 60. The engagement of the underside of pistons 59 with the cross head 30 prevent the under face of the panel elements 56 from being forced below the surrounding face of the frame elements 57.

70 The cylinders 60 are in communication with each other by means of the channel 62, see Fig. 4, and are adapted to be brought into communication with cylinder 63 by means of the passage 64, controlled by the 75 rotary cam actuated valve 65. There is another passage 66 between the cylinders 60 and cylinder 63, which is controlled by the check valve 67, see Figs. 2 and 13. Cylinder 63 is provided with the piston 68, which is 80 controlled by a number of springs 69. These springs are set by means of the top plate 70 and bolts 71, with a tension to give the required pressure per square inch on the panel plungers 56. The cylinders and communicating spaces are filled with a liquid sufficient in quantity to move piston 68 upwardly against the pressure of springs 69, preferably to provide a space between the 85 top of cylinder 63 and the underside 72, of formation 73, which carries the piston 68. The number of springs 69 pressing down on the upper piston 68 is not necessarily fixed. Ten springs are shown. The advantage of 90 a large number of springs over a few, is that they are more flexible and do not change their pressure so much for a given movement. These springs are also quite long, thus having a large number of coils in them. With this construction, piston 68 can vary 95 its position, in cylinder 63 considerably, without unduly affecting the pressure of the springs. This permits a reasonable variation in the amount of liquid in the cylinders. However, when the amount of liquid becomes 100 depleted to a certain point, more liquid must be pumped in.

105 The valve 65 is operated by the mechanism shown in Figs. 2, 11 and 12. The valve member 65, has an arm 75 provided with the roller 76, and normally controlled, and held in closed position, by the spring 77, a stop 78 limits the spring actuated movement of arm 75. A cam member 79 secured to the stationary tie frame 51, engages the 110 roller 76 to open the valve upon predetermined movement of the cross-head 30.

115 The check valve 67 is gravity actuated and permits the passage of fluid in one direction only, that is from cylinders 60 to cylinder 63.

120 The cutting or shaving device for removing the panel may be either in the form of a knife or a wire. In Figs. 6 to 10 and 14 to 19, a knife is shown. These cutting knives 125 80 are clamped by the clamps 81 to the lower end of frame structures 82, adjustably supported by the beam 83. Adjustment is secured by means of the thumb screw 116, and the frames are locked in position of adjust-

ment by means of the slot and bolt connections 84 and 85. This angle beam 83 is connected to the ends of levers 86 mounted on shaft 87, see Fig. 10. Shaft 87 carries lever 88 having the roller 89 which cooperates with the cam 90 on shaft 34. The depressed part 91 of cam 90 gives the knife or blade 80 the down and up movement into and out of the cutting position.

10 To these frame structures 82 are also secured the brackets 94 to which are pivotally mounted, as at 95, the cam 96 carrying the chip or shaving catchers 97. This cam 96 is controlled by spring 98 and is operated 15 into the discharging position against spring tension, by the roller 99 on lever or arm 46 of the charging mechanism. The plate or shield 100 acts as a stop for catcher 97 and also prevents the discharge of the chip or 20 shaving 101 until the catcher 97 is tilted into the discharging position, as shown in Fig. 14. The roller 99 is adjustably mounted in slot 102 of arm 46.

The shaving knife 80 is beveled on its 25 underside, as at 103, see Fig. 30, for slicking the top of the brick, after the shaving is removed, in order to prevent or smooth out any particles raised above the surface of the brick by the action of the shaving blade. 30 In case a cutting wire is used, a similar slicker device 104 is shown in Fig. 26. A slide plate 115 is provided back of the blade 80 to convey the chip or shaving 101 to the chip catcher 97.

35 In Figs. 21 to 26 inclusive, a construction is shown similar to that shown in Figs. 14 to 20 inclusive, except that a cutting wire is provided instead of a cutting blade. The operation is substantially the same as that 40 of the cutting blade as hereinafter described. The wire 105 is secured to a yoke or frame formation 106. One loop 107 of the wire is secured on the pin or stud 108. The wire is then passed over the two horns 109 with the 45 loop at the other end of the wire secured to the pin or stud 110, mounted on the lever 111, pivoted at 112 and provided with the tension thumb screw 113, engaging the lug 114, for securing the proper tension of the 50 wire, see Fig. 25. A slide plate 115 is provided back of the wire to convey the chip or shaving 101 to the chip catcher 97.

In operation:

The brick clots, indicated as *a*, are fed by hand onto the table 55 in front of the charger element 44; this charger element pushing them into position over the lower plunger 35, which at the beginning of this 55 operation is in the elevated position in the mold box 117, and its top surface is flush with the top surface of the mold box and with the surface of table 55. Before the 60 clots reach their final position on plunger 35, however, the plungers have been lowered slightly so that the rear wall of the

mold box will act as a stop to prevent the clots from sliding past the margin of the mold box.

The lower plungers continue to descend with the upper plungers following and 70 pressing the clots in the manner to be explained.

The charging mechanism operates as follows:—

The charger element 44 pushes the clots 75 in position upon the lower plungers as above described. The initial position of the clots *a* on the table 55 is shown in Fig. 6. The final position of the clot on plunger 35 ready for pressing is shown in Fig. 8. 80 After the clots have been pressed, they are carried up by the lower plunger 35 to level of the top of the mold box as shown, as *b*, in Fig. 6. When the charger frame moves forward, the element 45 pushes the bricks off 85 the plungers 35 along the top surface 118 of the mold box 117 so that the panel 119 of the brick will engage the knife 80, which has been lowered for the purpose, as shown 90 in Fig. 7. It should be noted however that the knife is elevated until the head of the brick has passed beneath it; it is then lowered to engage the panel 119, and after cutting through the panel, is again elevated to 95 clear the surface of the brick at the tail end thereof. The width of the blade is slightly greater than that of the panel, but narrower than the top surface of the brick, so that the top surface of the brick is not engaged or 100 marred by the cutting blade. The blade is 105 depressed so as to cut the panel flush with, or slightly below the surrounding surface of the brick to produce a face that will not interfere with stacking or laying the bricks. This operation of the blade or knife is secured by the form of the depression 91 of cam 90 as already described. The adjustment of this depression is secured by the slotted element 120 shown in Fig. 10. Fig. 8 shows the position of the cutting blade 80 110 after it has completed the cut of the panel. It will be noted that the surface 118 of the mold box is extended to project beneath the brick on a vertical line below the point of engagement of the cutting edge of the blade 115 80 in order to support the brick during the cutting operation. From the surface 118 the brick passes onto the off-bearing belt 121. The shaving or chip 101 passes above 120 the knife onto the chip catcher 97 as shown in Figs. 8 and 9. After the bricks have passed beneath the chip catcher 97, the chips 101 are dumped by the catcher 97 onto the belt 121 behind the brick.

125 After the panel has been severed, the charger frame is moved back sufficiently so that elements 44 and 45 will clear the upper plungers as they descend. The charger frame remains in this position while the upper plungers press the brick and return a 130

sufficient height to permit the element 45 to move back over the mold box into initial position before the lower plunger pushes the pressed brick up into its path, as shown in Fig. 6. These operations of the charger frame are secured by the cam 50 and associated mechanism above described.

The chief function of the lower plungers is to discharge the bricks from the mold box after they have been pressed. They do however have a slight upward or pressing movement toward the end of the downward pressing movement of the upper plungers in order to apply pressure to both surfaces of the bricks at the same time. This is secured by the raised position 122 on the face of the cam 37, see Fig. 2.

The control mechanism for the panel element 56 is mounted on the cross-head 30. The two cylinders 60, one for each plunger element 56, and the cylinder 63, are all rigidly mounted on the cross-head 30. The elements 56 are secured to piston rods 58, which in turn are connected to pistons 59 operating in cylinders 60. The piston 68 operating in cylinder 63 is connected to the housing or element 73, having the flange 73' against which the lower ends of springs 69 engage. The upper ends of these springs engage the cap plate 70 held in position by the bolts 71 threading into the cross-head 30. These bolts 71 secure the desired tension of the springs upon piston 68. The cylinders are maintained in communication by means of the channel 62, so that the pressure in cylinders 60 will always be equal. This insures the same pressure on both brick clots although one clot may have more material than the other, provided both clots contain enough material to fill the mold box completely.

When the cross-head 30 descends the plunger elements 57 press the clots against the lower plungers 35. This brings the margins of the faces to exact size. The surplus material forces the panel plungers upward. This results in a corresponding upward movement of pistons 59 which forces liquid from cylinders 60 past check valve 67 into cylinder 63 against the pressure of springs 69 acting on piston 68. When the cross-head 30 ascends, it is important that the panel elements of the plungers lift simultaneously with the surrounding frame elements. That is, the difference in the two levels must be maintained until the plungers as a whole, are well clear of the brick. Otherwise the panel element would flatten out the panel just raised, and thus distort the brick. Therefore when the pressure is taken off the plungers the check valve 67 prevents the liquid from returning from cylinder 63 back to cylinders 60. The springs 61 hold the pistons 59 up against the liquid in cylinders 60 until the cross-

head 30 reaches a point where the cam 79 engages roller 76 to open valve 65, whereupon the liquid in cylinder 63 under pressure of springs 69 immediately forces the panel plungers down until their lower faces 70 are flush with the surrounding face of the frame elements 57.

The operation of the press is shown progressively in Figs. 6 to 10 inclusive.

In Fig. 6 the brick or clot *a* has just been slid in front of the charger element 44 from the position shown in dotted lines on the inclined plate 124; this part of the operation is done by hand. Brick *b* has been pressed and raised by the lower plunger to a position in front of the charger element 45 and ready to be delivered by it. The upper plunger 35 has reached its highest position and is now ready to descend. Brick *c* has passed under the shaver and is traveling on the off-bearing belt ready to be taken off by hand. The chip catcher has dumped the chip of the raised panel; this is also being carried away by the off-bearing belt.

In Fig. 7, brick or clot *a* is being pushed into position on the lower plunger, while passing under and in contact with an oiling roll 53, which puts a film of oil on the top surface of the clot to prevent material from sticking to the face of the upper plunger when in pressure contact with the clot. Brick *b* is being pushed under the shaver, the chip or slab 101 passing over the top of the blade 80. During this operation the brick is firmly and accurately supported by the upper surface 118 of the mold box which is extended here for this purpose. Brick *c* is advanced somewhat further with the off-bearing belt. In this Fig. 7, the upper plunger has descended part way, while the lower plunger has remained stationary.

In Fig. 8, the charger has pushed the brick or clot *a* entirely upon the lower plunger. The lower plunger has started to descend just previous to this, so that a part of the rear wall of the mold box will form a stop to prevent the clot from slipping too far, and to assure its stopping when the charger stops. The lower plunger descends rapidly from this point, with the upper plunger following. Brick *b* has also been pushed as far as the charger element 45 will push it. The panel is entirely shaved off and the shaving blade and chip catcher have been elevated to clear the brick; the brick is now free to be carried away on the off-bearing belt. Brick *c* is still farther advanced on the off-bearing belt. The charger will now move back slightly to the position shown in Fig. 9, so that the upper plungers will clear it.

Fig. 9 shows brick *a* pressed in the mold box, with the raised panel formed. The frame element of the upper plunger has been forced to a predetermined position, making

the brick, as to its outer margins, exactly the desired thickness: the panel element of the plunger has been raised, against the spring pressure, sufficiently to accommodate the surplus material, meantime bricks *b* and *c* have advanced on the off-bearing belt.

In Fig. 10, the upper plunger is ascending with the panel element thereof still elevated above the surrounding frame element. At 10 a given point in this ascent the valve between cylinders 60 and cylinder 63 is opened and panel element is forced down as already described.

The charger now goes back, the lower 15 plunger then pushes the brick up flush with the top of the mold box ready to be pushed off by the charger as shown in Fig. 6.

Fig. 10 shows the cam 50 that operates the charger and also cam 90 that raises and 20 lowers the cutting blade or cutting wire. This figure also shows the position of the crank 33 that operates the upper plungers.

The machine illustrated in the drawings 25 is what is called a double repress, pressing two standard bricks at one pressure. However, for larger block, single mold boxes and plungers are used, pressing one at a stroke.

The brick has its sides, ends, bottom and a 30 substantial margin of the top face pressed into exact dimension; surplus material being pressed into a projecting point. The entire brick and panel is however subjected to substantially predetermined pressure, during the entire pressing operation.

35 What I claim is:—

1. The method of repressing bricks, which 40 consists in applying pressure thereto in such manner as to bring all the faces of the brick into exact dimension, except one face, with respect to which the margin is brought into exact dimension, while surplus material is permitted to project beyond the plane of 45 said margin.

2. The method of repressing bricks, which 50 consists in applying pressure thereto in such manner as to bring all the faces of the brick into exact dimension, except one face, with respect to which the margin is brought into exact dimension, while surplus material is 55 permitted to project beyond the plane of said margin, and maintaining said projecting portion under a substantially predetermined pressure during the entire pressing operation.

3. The method of repressing bricks, which 60 consists in applying pressure thereto in such manner as to bring all the faces of the brick into exact dimension, except one face, with respect to which the margin is brought into exact dimension, while surplus material is permitted to project beyond the plane of 65 said margin, and then removing said projecting portion.

4. The method of repressing bricks, which 65 consists in applying pressure thereto in such

manner as to bring its sides, ends, bottom and a substantial margin of its top face into exact dimension while permitting surplus material to project above the surrounding margin of said top face, and maintaining 70 said projecting portion under a substantially predetermined pressure during the entire pressing operation and then removing said projecting portion so as to bring the entire top face of the brick into substantially one plane. 75

5. The method of repressing bricks, which 80 consists in applying pressure thereto in such manner as to bring its sides, ends, bottom and a substantial margin of its top face into exact dimension while permitting surplus material to project above the surrounding margin of said top face and then shaving the projecting portion in a plane corresponding substantially with said surround- 85 ing margin.

6. The method of repressing bricks, which 90 consists in applying pressure thereto in such manner as to bring its sides, ends, bottom and a substantial margin of its top face into exact dimension while permitting surplus material to project above the surrounding margin of said top face and maintaining a yielding pressure on said projecting portion during the entire pressing operation. 95

7. The method of repressing bricks, which 100 consists in applying pressure thereto in such manner as to bring its sides, ends, bottom and a substantial margin of its top face into exact dimension while permitting surplus material to project above the surrounding margin of said top face and maintaining said projecting portion under a substantially predetermined pressure during the entire pressing operation, and relieving the 105 pressure upon the projecting portion and upon the main body of the brick simultaneously.

8. The method of repressing bricks, which 110 consists in bringing all the faces of the brick, except the middle part of one face, into exact dimension, and permitting said middle part to project above the face to the extent required by surplus material in the brick. 115

9. The method of repressing bricks, which 120 consists in bringing all the faces of the brick, except the middle part of one face, into exact dimension, permitting said middle part to project above the face to the extent required by surplus material in the brick, and maintaining all parts of the brick under pressure during the entire repressing operation.

10. The method of repressing a plurality 125 of bricks simultaneously, which consists in bringing all the faces of each brick, except the middle part of one face of each brick, into exact dimension, and permitting said middle part to project above said face to the 130

extent required by surplus material in the brick, and maintaining all the bricks under the same pressure during the entire repressing operation.

5. 11. In a brick repressing machine, the combination of a mold element, and plunger elements and operating mechanism associated and operating to bring all faces of the brick into exact dimension except the middle part of one face and to permit said middle part to project above said face to the extent required by surplus material in the brick.

10. 12. In a brick repressing machine, the combination of a mold element and plunger elements and operating mechanism associated and operating to bring all faces of the brick into exact dimension except the middle part of one face and to permit said middle part to project above said face to the extent required by surplus material in the brick, and means for maintaining a substantially constant pressure upon said middle part during the entire repressing operation.

15. 13. In a brick repressing machine, the combination of a mold box and plunger elements and operating mechanism associated and operating to bring all faces of the brick into exact dimension except the middle part of one face and to permit said middle part to project above said face to the extent required by surplus material in the brick, and means for maintaining a yielding pressure upon said middle part during the entire repressing operation.

20. 14. In a brick repressing machine, the combination of a mold box and plunger elements and operating mechanism associated and operating to bring all faces of the brick into exact dimension except the middle part of one face and to permit said middle part to project against yielding pressure above said face to the extent required by surplus material in the brick.

25. 15. In a brick repressing machine, the combination of a mold box and plunger elements and operating mechanism associated and operating to bring all faces of the brick into exact dimension except the middle part of one face and to permit said middle part to project above said face to the extent required by surplus material in the brick, and means for removing said middle part.

30. 16. In a brick repressing machine, the combination of a mold box and plunger elements and operating mechanism associated and operating to bring all faces of the brick into exact dimension except the middle part of one face and to permit said middle part to project above said face to the extent required by surplus material in the brick, and means for removing said middle part and for smoothing said face.

35. 17. In a brick repressing machine, the combination of a mold box and plunger elements and operating mechanism associated

and operating to bring all faces of the brick into exact dimension except the middle part of one face and to permit said middle part to project above said face to the extent required by surplus material in the brick, and means for removing said middle part to approximately the plane of the surrounding margin.

40. 18. In a brick repressing machine, the combination of a mold box and plunger elements and operating mechanism associated and operating to bring all faces of the brick into exact dimension except the middle part of one face and to permit said middle part to project above said face to the extent required by surplus material in the brick, and means for removing said middle part, so as to leave a surface within the margin of said face slightly below the plane of said margin.

45. 19. In a brick repressing machine, the combination of a plurality of mold boxes, cooperating plunger elements operating mechanism associated and operating to bring all the faces of a plurality of bricks into exact dimension except the middle part of one face of each brick and to permit said middle part to project above said face to the extent required by surplus material in the brick, and means for exerting an equalized pressure on all the bricks during the entire repressing operation.

50. 20. In a brick repressing machine, the combination of a mold box and oppositely acting plungers, one plunger being composite, comprising a panel element and a surrounding frame element, means for operating the frame element and the oppositely acting plunger with definite strokes, and means for operating the panel element, comprising a cylinder, a piston operating therein, and means for supplying fluid under pressure to said cylinder.

55. 21. In a brick repressing machine, the combination of a plurality of mold boxes and cooperating oppositely acting plungers, one of each pair of cooperating plungers being composite, comprising a panel element and a surrounding frame element, means for operating the frame element and the oppositely acting plunger with definite strokes and means for operating the several panel elements with an equalized yielding pressure.

60. 22. In a brick repressing machine, the combination of a plurality of mold boxes and cooperating oppositely acting plungers, one of each pair of cooperating plungers being composite, comprising a panel element and a surrounding frame element, means for operating the frame element and the oppositely acting plunger with definite strokes and means, comprising communicating cylinders, pistons operating therein and means for supplying fluid under pressure to said cylinders, for operating the several

panel elements with an equalized yielding pressure.

23. In a brick repressing machine, the combination of a mold box, oppositely acting plungers cooperating therewith, one plunger being composite comprising a panel element and a surrounding frame element, means for operating the frame element and the opposite plunger with definite strokes, and means for operating the panel element with a yielding pressure stroke, comprising a fluid containing cylinder, a piston operating therein, a second fluid containing cylinder communicating with the first cylinder, a piston operating therein, and means moving with the frame element connected by a plurality of springs to actuate the last mentioned piston for forcing liquid to the first mentioned cylinder.

24. In a brick repressing machine, the combination of a mold box, oppositely acting plungers cooperating therewith, one plunger being composite comprising a panel element and a surrounding frame element, means for operating the frame element and the opposite plunger with definite strokes, and means for operating the panel element with a yielding pressure stroke, comprising a fluid containing cylinder, a piston operating therein, a second fluid containing cylinder communicating with the first cylinder, a piston operating therein, means moving with the frame element connected by a plurality of springs to actuate the last mentioned piston for forcing liquid to the first mentioned cylinder, and valves for controlling the flow of liquid from one cylinder to the other.

25. In a brick repressing machine, the combination of a mold box, oppositely acting plungers cooperating therewith, one plunger being composite comprising a panel element and a surrounding frame element, means for operating the frame element and the opposite plunger with definite strokes, means for operating the panel element with a yielding pressure stroke, comprising a fluid containing cylinder, a piston operating therein, a second fluid containing cylinder communicating with the first cylinder, a piston operating therein and means moving with the frame element connected by a plurality of springs to actuate the last mentioned piston for forcing liquid to the first mentioned cylinder, and means for adjusting the initial tension of the springs.

26. In a brick repressing machine, the combination of a mold box, oppositely acting plungers cooperating therewith, operating mechanism associated and operating to bring all the faces of the brick to exact dimension, except the middle part of one face and to permit said middle part to project above said face to the extent required by surplus material in the brick, means for severing said middle projecting part from the

brick, and a charging device for simultaneously delivering a clot to the mold box and for moving a repressed brick to cooperate with the severing means.

27. In a brick repressing machine, the combination of a mold box, oppositely acting plungers cooperating therewith, operating mechanism associated and operating to bring all the faces of the brick to exact dimension, except the middle part of one face, and to permit said middle part to project above said face to the extent required by surplus material in the brick, means for severing said middle projecting part from the brick, a charging device for simultaneously delivering a clot to the mold box and for moving a repressed brick to cooperate with the severing means, and means for diverting the severed part.

28. In a brick repressing machine, the combination of a mold box, oppositely acting plungers cooperating therewith, operating mechanism associated and operating to bring all the faces of the brick to exact dimension, except the middle part of one face and to permit said middle part to project above said face to the extent required by surplus material in the brick, means for severing said middle projecting part from and smoothing the face of the brick, a charging device for simultaneously delivering a clot to the mold box and for moving a repressed brick to cooperate with the severing and smoothing means.

29. In a brick repressing machine, the combination of a plurality of mold boxes, a plurality of pairs of cooperating oppositely acting plungers, one of each pair of plungers being composite, comprising a panel element and surrounding frame element, means for operating the frame elements and opposite plungers with definite strokes, means for operating the panel elements comprising communicating fluid containing cylinders, pistons operating therein, means connecting the pistons to the panel elements, a common fluid containing cylinder adapted to communicate with the first mentioned cylinders, a piston operating therein, a spring supporting element connected to said piston, a plurality of springs having their lower ends engaging said element, a top plate engaging the upper ends of said springs and connected to the means actuating the frame elements, means forming a passage having a check valve for permitting flow from the first mentioned cylinders to the common cylinder, means forming a second passage between the first mentioned cylinders to the common cylinder, a valve for controlling said passage and means operated by moving parts of the machine for controlling said valve.

30. In a brick repressing machine, the combination of a plurality of mold boxes, a plurality of pairs of cooperating oppositely

acting plungers, one of each pair of plungers being composite, comprising a panel element and a surrounding frame element, means for operating the frame elements and opposite plungers with definite strokes, means for operating the panel elements comprising communicating fluid containing cylinders, pistons operating therein, means connecting the pistons to the panel elements, a common fluid containing cylinder adapted to communicate with the first mentioned cylinders, a piston operating therein, a spring supporting element connected to said piston, a plurality of springs having their lower ends 10 engaging said element, a top plate engaging the upper ends of said springs and connected to the means actuating the frame elements, means forming a passage having a check valve for permitting flow from the first mentioned cylinders to the common cylinder, means forming a second passage between the first mentioned cylinders to the common cylinder, a valve for controlling said passage, means operated by moving parts of 20 the machine for controlling said valve, and springs for pressing the pistons against the liquid pressure in the first mentioned cylinders.

31. In a brick repressing machine, the 30 combination of a plurality of mold boxes, a

plurality of pairs of cooperating oppositely acting plungers, one of each pair of plungers being composite, comprising a panel element and a surrounding frame element, means for operating the frame elements and opposite plungers with definite strokes, means for operating the panel elements comprising communicating fluid containing cylinders, pistons operating therein, means connecting the pistons to the panel elements, a common fluid containing cylinder adapted to communicate with the first mentioned cylinders, a piston operating therein, a spring supporting element connected to said piston, a plurality of springs having their lower ends 35 engaging said element, a top plate engaging the upper ends of said springs and connected to the means actuating the frame elements, means forming a passage having a check valve for permitting flow from the first mentioned cylinders to the common cylinder, means forming a second passage between the first mentioned cylinders to the common cylinder, a valve for controlling said passage, means operated by moving parts of the machine for controlling said valve and means for limiting 40 the downward movement of the panel elements.

HOWARD K. KING.
